US00D985108S

(12) **United States Design Patent** (10) **Patent No.:** **US D985,108 S**
Huang et al. (45) **Date of Patent:** **** May 2, 2023**

(54) **JOINT FOR ABOVE GROUND POOL FRAME**

(71) Applicant: **Intex Marketing Ltd.**, Tortola (VG)

(72) Inventors: **Zhi Xiong Huang**, Xiamen (CN); **Ai Ming Tan**, Xiamen (CN)

(73) Assignee: **Intex Marketing Ltd.**, Tortola (VG)

(**) Term: **15 Years**

(21) Appl. No.: **29/768,908**

(22) Filed: **Feb. 2, 2021**

Related U.S. Application Data

(62) Division of application No. 29/708,749, filed on Oct. 9, 2019, now Pat. No. Des. 930,802.

(57) **CLAIM**

The ornamental design for a joint for above ground pool frame, as shown and described.

DESCRIPTION

FIG. 1 is a front perspective view of a joint for above ground pool frame showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The long-short broken lines within the openings depict boundaries that form no part of the claimed design. The evenly-sized broken lines depict portions of the joint for above ground pool frame that form no part of the claimed design.

1 Claim, 7 Drawing Sheets
